UNITED STATES PATENT OFFICE.

ANDREW MUIRHEAD, OF HAVERHILL, MASSACHUSETTS, AND EVERETT K. MANSFIELD, OF WHITE PLAINS, NEW YORK.

PULP HYDRATOR.

Application filed December 30, 1925. Serial No. 78,498.

To all whom it may concern:

Be it known that we, ANDREW MUIRHEAD, of Haverhill, county of Essex, State of Massachusetts, and EVERETT K. MANSFIELD, of White Plains, county of Westchester, State of New York, citizens of the United States, have invented an Improvement in Pulp Hydrators, of which the following is a specification.

10 In the process of preparation of chemical pulp for the paper machine, the operation of hydrating and defelting ground wood, paper and other cellulose fibrous material has usually, or almost universally been performed 15 in the pulp beater.

As the primary purpose of this operation is to cause the fibers to be separated and chemically united with water, no beating or grinding action, which forcibly tears apart 20 the fibers is necessary, so that, in order to avoid as much as possible, the cutting of the fibers by the beater roll, the roll is run at a substantial distance above the bed, and, to a large extent merely acts as a circulating 25 pump, that is, the hydrating process is, to a large degree effected, and may, practically be entirely effected, by the rubbing action of the fibers on each other as they are circulated. Consequently, the greater the relative motion or rubbing action of the fibers 30 as the pulp is circulated, the greater will be the hydrating and defelting action.

In the pulp beater, while some relative movement of fibers on each other is caused 35 by the flow of the pulp about the channel of the beater, yet this flow is very sluggish, largely due to the fact that the roll cannot be rotated above a certain speed without throwing the pulp back over itself, and 40 there is normally but little relative movement of the fibers, for, unless disturbed by other means than the roll, the fibers tend to remain in practically the same relative position during nearly the whole of the travel 45 about the vat, so that, normally, comparatively little rubbing action of the fibers on each other takes place. Moreover, it is well known that the chief objection to the use of the beater for this purpose is the 50 lack of uniformity of its action on the pulp, due to the fact that the pulp nearest the mid-feather normally travels under the roll more frequently than that nearest the sides. Another important objection to the 55 use of the beater for hydrating purposes is

the slow speed at which the operation is performed, also, while the roll is usually operated at some distance from the bed to avoid cutting the fibers, yet, in practice, even under these conditions the blades of the 60 roll have an undesirable cutting effect.

The objects of our invention are to provide an improved apparatus for hydrating and separating cellulose fibers, where mechanical action in tearing apart the fibers 65 is unnecessary, in which the extent of the relative motion or rubbing action of the fibers, or portions of the mass, on each other will be greatly increased, as compared with the action in the ordinary beater, and the 70 speed of circulation and relative motion will be greatly accelerated, so that the time required for the required hydrating and defelting action will be greatly reduced, and in which the liability that the fibers will 75 be cut during the operation will be entirely obviated.

We accomplish these objects, primarily, by providing a completely enclosed fluid circulatory system, in which the circulating 80 agent is preferably a suitable form of centrifugal pump, and in which the form and cross sectional area of the circulatory passages are so varied that the velocity of the pulp at different portions of the circuit is 85 constantly being varied by means of reverse and accelerated currents, and currents which are variably reduced in speed at different points in the travel through the circuit, so that relative displacement of the fibers is 90 constantly taking place throughout the entire mass and is taking place at a high speed in certain portions, and rapidly in other portions, as compared with prior practice, 95 and so that the entire mass will be operated on with practically perfect uniformity.

For a more complete understanding of our invention, reference is made to the accompanying drawing in which:

Fig. 1 is a side elevation of a preferred 100 embodiment of the invention.

Fig. 2 is an end view thereof and

Fig. 3 is a sectional view at line $\alpha-\alpha$ of 105 Fig. 2.

In providing means for causing circulation of the pulp through the circuit hereafter more specifically described, a pair of centrifugal pumps 2 and 4 of well known form are preferably employed, although other types of rotary pumps may also be 110

effectively employed, and in which the impeller comprises a series of rearwardly curved blades 5.

According to our invention, an upright discharge pipe 6 and 8 is extended from the discharge port of each pump to a height sufficient to give the head necessary to secure efficient operation, each being connected to an elbow section 7 and 9, so that the discharge therefrom will be approximately horizontal.

A pair of tubular casings, forming mixing and circulation chambers, are provided, which comprise funnel shaped head sections 10 and 12, central openings in the ends of which are respectively connected to the discharge ends of the pipe elbows 7 and 9, intermediate cylindrical sections 13 and 15, to which the base ends of the head sections are connected, and tail sections 16 and 18, which are connected to the opposite ends of sections 13, 15 and are, in turn, connected, by pipe elbow sections 17 and 19, to the inlet ports of the pumps 4 and 2 respectively. The internal diameters of the intermediate sections are somewhat more than twice and preferably nearly three times as great as the internal diameters of the discharge and intake pipes to the pumps, and the tail sections 16, 18 taper in diameter from the full diameter of the intermediate sections to that of the inlet pipes to the pumps, said inlet and discharge pipes being of approximately the same diameter. The casing sections are also arranged to decline from the level of the discharge ends of the elbows 7, 9, the extent to which they decline being preferably sufficient to cause a substantial acceleration in the flow, so that the whole circuit may be readily drained through dump pipes 20, 22 which are connected to the bases of the vertical discharge pipes 6, 8. The tapering tail sections are also formed so that the bottom portions thereof extend at the inclination of, and continuously with the bottom portions of the intermediate sections, so that, when the circuit is drained, practically all the pulp may be readily washed therefrom. The construction is also such that there will be no dead spaces in which the pulp does not circulate, as the operation is being performed.

Vertical filling pipes 24, 26 are connected to the upper portion of each head section 10, 12, covers 25, 27 being provided for closing the same, and baffle plates 28, 30 are provided in said head sections, which extend upwardly from the upper portions of the inlet ports, to which the elbow sections 7, 9 are connected, in a 90° curve and then vertically into the filling pipes to points at a suitable distance from the covers 25, 27.

In operating the apparatus, the whole circuit will be completely filled with water and a suitable quantity of somewhat disin-

tegrated ground wood, paper, or other cellulose fiberous material, and the covers 25, 27 will be closed. The pumps will be operated at a suitable speed, so that the material will be forced up the discharge pipes 6 and 8 and into the relatively large chambers and through the same to the intake side of the pumps, the arrangement being such that the material will pass through one pump and the directly connected circulation pipes and chambers and then through the other pump and chambers in order. As the material, or stuff is forced into the head section of each chamber 13, 15, the effect will be similar to that of a jet discharged under the surface of a substantially larger body of water, that is, the force of the jet will be dissipated in the larger mass by causing an acceleration of the flow in its middle portion, also, the rapid flow at the point where the jet enters the casing tends to pick up and carry along the surrounding material in a manner to cause a reverse flow near the walls of the casing. The point at which the force of the jet will be completely dissipated depends on various conditions, such as speed of the jet at its point of delivery to the casing and the consistency of the charge, and is preferably such that it will cause acceleration throughout at least half the length of the casing. As the material passes into the tapering tail-sections, acceleration in flow will again take place until its speed reaches the maximum on entering the inlet pipes to the pumps. The circulation in each casing is thus caused by the forcing action of one pump and the suction action of the other. Consequently, in passing from the outlet of the elbows 7, 9 to the inlet to the elbows 17, 19, the material will be caused to flow at various speeds in different portions, and the various currents and counter currents, in which the material will be carried, will cause relative rubbing actions of different portions thereof on each other, so that the defelting and hydrating action will be rapidly carried on.

In addition to the diverse currents which will thus be made to flow in the casing, the baffle plates 28, 30 will appreciably increase the complexity of the circulation by intercepting a portion of the jet which is projected from each discharge pipe and causing it to flow upwardly between said plates and the adjacent sides of the tubes 24, 26. This partial jet from the main jet will be delivered into the top portion of said tubes and cause a down flow in the remaining portion, which will meet the return flow in the upper portion of the chamber caused by the projection of the jet therein, as previously described. The baffle plates also prevent lodgment of the stuff in the filling pipes, the circulation therein being as active as in other portions of the system.

When the material has been circulated for

a sufficient length of time to complete the operation, the dump pipes will be opened, so that the material may be discharged and all pulp may be readily washed from the 5 pipes and casings and then they may be refilled and the operation repeated, the pumps being continuously operated at all times.

The above described apparatus is considered to have numerous advantages over 10 the ordinary beater, primarily because the action on the material is uniform and the hydrating operation is performed much more rapidly than in an ordinary beater, and 15 also because it does not cut the fibers.

The apparatus is primarily useful, in 20 practice, as a secondary beater, as it is often considered desirable to circulate the stock in an ordinary beater until it is thoroughly 25 broken up and mixed with water, as a preliminary to the hydrating operation. In many instances, however, the stock will be sufficiently disintegrated by passing it thru a shredder before delivering it to the above 30 described apparatus.

We claim:

1. A pulp hydrator comprising a pump having inlet and discharge pipes connected thereto and an elongated tubular casing of 35 substantially greater transverse area than the area of said pipes and connected at its ends to said pipes, respectively, to form a closed fluid circuit through which the fluid may be circulated by said pump, said discharge pipe from the pump being arranged to project a jet into said casing longitudinally thereof.

2. A pulp hydrator comprising a rotary 40 pump having an inlet and a discharge pipe of uniform transverse area connected thereto, an elongated tubular casing of substantially greater transverse area than that of said pipes and having said inlet pipe connected thereto at one end and said discharge 45 pipe connected to the opposite end, to form a closed fluid circuit, the portions of said casing at each end being formed to taper to said pipes, respectively, to prevent lodgment of the material therein as it is circulated.

50 3. A pulp hydrator comprising a rotary pump having inlet and discharge pipes of uniform area connected thereto, an elongated tubular casing of substantially greater transverse area than that of said pipes, said discharge pipe being connected to one end of said casing in position to deliver a jet thereto longitudinally of the middle thereof, and said inlet pipe being connected to the opposite end of said casing to 55 form a closed fluid circuit.

4. A pulp hydrator comprising a rotary 60 pump having inlet and discharge pipes of uniform transverse area, an elongated tubular casing of substantially greater transverse 65 area than that of said pipes, and having its

end portions tapering to openings corresponding in size to the passageways in said pipes and to which said pipes are respectively connected to form a closed fluid circuit, said discharge pipe being arranged 70 at the point of connection with said casing in position to direct a jet longitudinally of the middle of said casing.

5. A pulp hydrator comprising a rotary 75 pump having inlet and discharge pipes of uniform transverse area, an elongated tubular casing of substantially greater transverse area than that of said pipes, and having its end portions tapering to openings corresponding in size to the passageways in 80 said pipes and to which said pipes are respectively connected to form a closed fluid circuit, said casing being arranged to extend horizontally and said discharge pipe 85 being arranged to extend upwardly and then horizontally at the point of connection with said casing, in position to direct a jet longitudinally of the middle thereof and the bottom of said casing being arranged to decline from one of said openings to the 90 other.

6. A pulp hydrator comprising a centrifugal pump having a discharge pipe extending upwardly therefrom and having a 95 horizontally extending end portion, a horizontally disposed elongated tubular casing having an inlet port at one end of relatively smaller area than the transverse area of the casing, said end portion of said discharge 100 pipe being connected to said port and arranged to deliver a jet to said casing longitudinally of the middle thereof and a return pipe connecting the opposite end of said casing and the inlet to the pump.

105 7. A pulp hydrator comprising a centrifugal pump having a discharge pipe extending upwardly therefrom and having a horizontally extending end portion, a horizontally disposed elongated tubular casing 110 having an inlet port at one end of relatively smaller area than the transverse area of the casing, said end portion of said discharge pipe being connected to said port and arranged to deliver a jet to said casing longitudinally of the middle thereof, a filling pipe 115 opening to the upper side of said casing adjacent said port and extending upwardly therefrom, means for closing the upper end of said filling pipe, means arranged to deflect a portion of the jet into the upper portion of said filling pipe and a return pipe connecting the opposite end of said casing and the inlet to 120 said pump.

125 8. A pulp hydrator comprising a centrifugal pump having a discharge pipe extending upwardly therefrom and having a horizontally extending end portion, a horizontally disposed elongated tubular casing 130 having an inlet port at one end of relatively

smaller area than the transverse area of the casing, said end portion of said discharge pipe being connected to said port and arranged to deliver a jet to said casing longitudinally of the middle thereof, a filling pipe opening to the upper side of said casing adjacent said port and extending upwardly therefrom, means for closing the upper end of said filling pipe, a curved baffle plate extending horizontally from said inlet port and upwardly into said filling pipe in position to deflect a portion of the jet into the upper portion thereof and to cause a circulation upwardly and downwardly therein and a return pipe connecting the opposite end of said casing and the inlet to the pump. 15

10 In testimony whereof, we have signed our names to this specification.

ANDREW MUIRHEAD.
